UNITED STATES PATENT OFFICE

JOSEPH HOWELL ASH, OF BROOKLYN, NEW YORK.

KITCHEN RANGE OR PRESSURE BOILER.

SPECIFICATION forming part of Letters Patent No. 352,847, dated November 16, 1886.

Application filed April 13, 1885. Serial No. 162,094. (No model.)

To all whom it may concern:

Be it known that I, JOSEPH HOWELL ASH, a citizen of the United States, residing at Brooklyn, in the county of Kings and State of New York, have invented certain new and useful Improvements in Kitchen Range or Pressure Boilers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in boilers or reservoirs subject to high pressure; and it has for its object to make a joint between the head and main body which will sustain a higher degree of pressure than has been 20 possible in devices of similar character heretofore known.

The particular nature of my invention will hereinafter be fully described, and specifically pointed out in the claims.

25 In the drawings, Figure 1 is a plan view. Fig. 2 is a side elevation. Fig. 3 is a partial section on the line xx of Fig. 1. Fig. 4 is a perspective view of the head which slips into and closes the end of the main body, and Fig. 30 5 is a perspective of the outer ring or band which slips over the end of the casing and down against the outer portions of the head.

The shell or main body a of the boiler is of any ordinary form, having open ends, into 35 which the end piece or head b fits snugly. The head b is provided with the depending rim b' , which fits snugly into the open end and against the sides of the casing, where it is secured by a sweat-joint, and has the usual ports, b^2 b^3 , the 40 one port being for the ingress of water or steam, in the ordinary manner.

c is the outer ring or band, adapted to slide over and fit snugly against the side of the boiler shell or body a , and it has a wire, c' , 45 spun into its inner end, as shown, so as to form a shoulder, against which the driving-tool will strike. Its outer end is provided with an inwardly-turned flange or rim, c^2 , which laps over and fits snugly upon the outer portion of 50 the head b and over the joint between the said rim and casing.

When the parts are placed together, as shown in Fig. 3, the head will be flush with and the flange of rim c^2 of the outer ring or band will rest on the end of the shell or body a and overlap the outer portions of the head and the intervening joint. The band c encircles the shell and embraces the head, and is secured to each by a sweat-joint.

The head and retaining band are secured to 60 the body by a "sweat-joint," formed in any well-known manner—for instance, by placing a small quantity of solder upon the joint and melting it by heating the body, when it (the solder) will flow and fill the space between the 65 sides of the body and the sides of the rim of the head and the band and its overlapping flange. As but very little solder is employed, owing to the close proximity of the adjacent faces of the parts, a mere film of the metal intervenes between said parts, and a perfect 70 steam-tight joint will be maintained at all times, inasmuch as the joint will not be affected by heat or cold, because the several parts will expand and contract equally and simultaneously.

I make the head c and the rim b' of the head approximately of the same width; but this is a matter of preference only. When the joint is completed, I have a soldered surface equal 80 to the united lengths of the band c and the rim b' . The two soldered surfaces being supported by the overlapping flange c^2 , soldered to the head, makes a perfectly secure joint, and one not affecting the strength of the body.

Boilers as ordinarily constructed are weakest at the point of junction of the head with the body, owing to the removal of the metal for the passage of the rivets and the amount of strain produced by the upsetting of such 90 rivets. By my construction the head is not only firmly secured in place, but the boiler is stronger at its point of junction with the head than at any other point.

Having thus described my invention, what I 95 claim, and desire to secure by Letters Patent, is—

1. The combination of the boiler-shell, the head formed with a rim snugly fitting within the shell, and the ring formed of a portion 100 tightly encircling the shell, and an inwardly-projecting portion tightly embracing the head,

the three parts being secured together by sweat-joints.

2. The herein shown and described boiler-shell, in combination with means, as set forth, for heading the same, consisting of the head having inlet and egress ports, and a depending rim snugly fitted within the open end of the shell and secured in place by a sweat-joint, and the ring snugly fitting the exterior of the shell, and to having an inwardly-projecting flange extend-

ing over the junction between the rim and shell, and resting upon the top of the head, and secured to the shell and head by a sweat-joint, substantially as set forth.

In testimony whereof I affix my signature in presence of two witnesses.

JOSEPH HOWELL ASH.
